LIPSTICK DEVICE

James L. Younghusband, Chicago, Ill.

Application November 30, 1938, Serial No. 243,218

4 Claims. (Cl. 206—56)

My invention relates to a case for holding lipstick having means for projecting the lipstick for use and retracting it within the case for storage during nonuse.

Among the objects of my invention is to provide simple manually operable means for the quick projection and retraction of the lipstick, said means occupying small space not otherwise used in the case, and such other objects, advantages and capabilities as will later more fully appear and which are inherently possessed by my invention.

While I have shown in the accompanying drawings preferred embodiments of my invention, yet I wish it understood that the same are susceptible of modification and change without departing from the spirit of my invention.

Referring to the drawing Fig. 1 is a front elevation view of the exterior of my lipstick device; Fig. 2 is a sectional view on line 2—2 of Fig. 1; Fig. 3 is a sectional view on line 3—3 of Fig. 1; Fig. 4 is a vertical sectional view on line 4—4 of Fig. 1; Fig. 5 is a vertical sectional view on line 5—5 of Fig. 4 and Fig. 6 is a perspective detail view showing my cup and resilient member.

One embodiment selected to illustrate my invention comprises a hollow body member 10 having side walls 11 and open at the top and bottom. Positioned and movable within said body member 10 is a cup 20 adapted to hold lipstick 27 or the like.

Adjacent the lower portion of the body member 10 is a turnable member 40. The turnable member 40 is rotatably supported by oppositely disposed side walls 11, or the corners of the same when extending diagonally across the body member 10. Said turnable member 40 extends through the wall of the body member 10 on one end, and attached to said end is a wheel 24 manually operable from the exterior of the device. Attached to the turnable member 40 at substantially its center is a sprocket wheel 47.

A resilient member 46 is attached adjacent its upper end to the outer side of the cup 20 and extends downwardly within the body member 10 to the turnable member 40 where it is bent so that spaced openings 48 therein fit around the projections of the sprocket wheel 47. The resilient member 46 continues past the sprocket wheel 47 and is bent to extend upwardly along the inner side walls on the opposite sides of the body member 10.

When the wheel 24 is turned the turnable member 40 is also turned. When the wheel 24 is turned in one direction the turnable member 40

moves the sprocket wheel 47. The projections on the sprocket wheel 47 fit within the openings 48 of the resilient member 46 and move the resilient member 46 so that the resilient member shoves the cup 20 to the top of the body member 10 for use. When the wheel 24 is turned in the opposite direction the turnable member 40 turns and moves the sprocket wheel 47 so that its projections fitting within openings 48 pull the resilient member 46 so that it pulls the cup with its 10 lipstick 27 back into the body member 10 for storage during nonuse.

A bottom closure 34 is fitted by friction grip within a depression 36 in the lower outer ends of the side walls 11 of body member 10. A cap 28 15 is formed to fit over the open top of body member 10 by friction grip within depression 35 at the upper ends of the side walls 11.

The bottom closure 34 has attached thereto a bearing 49 for the resilient member 46; said bearing 49 may have a groove 50 for centering the resilient member therein so that the openings 48 in the resilient member meet the projections of the sprocket wheel 47.

Having thus described my invention, I claim: 25

1. A lipstick device comprising a hollow body member, a cup adapted to hold lipstick movable within said body member, a resilient member positioned within said body member and attached at its upper end to said cup, a turnable member 30 rotatably attached to the walls of said body member adjacent its lower portion, a wheel operable from the exterior of the device attached to said turnable member, a sprocket wheel attached to said turnable member, said resilient member 35 having a plurality of spaced openings, said resilient member extending down to and around said sprocket wheel so that the projections on the sprocket wheel fit within said openings, said resilient member continuing on upwardly on the 40 opposite side of said body member, said exterior wheel adapted upon being turned in one direction to turn the turnable member with its attached sprocket wheel so that the projections in the sprocket wheel fitting into the openings in 45 the resilient member will move the resilient member so that said resilient member will project the cup with its lipstick to substantially the top of the body member for use, said exterior wheel adapted upon being turned in the opposite direction to turn the turnable member and its sprocket so as to move the resilient member and cause it to pull the cup with its lipstick down within the body member for storage during nonuse, and closures for the open ends of the body member. 50 55

2. A lipstick device comprising a rectangular body member having a hollow interior, a round lipstick cup centrally positioned in said hollow interior so as to leave vacant corners between the 5 cup and the inner walls of said body member, a turnable member rotatably attached to the walls of said body member adjacent its lower portion, a wheel operable from the exterior of the device attached to said turnable member, a sprocket 10 wheel attached to said turnable member, a resilient member having one end attached to said cup and extending downwardly in one of said vacant corners within said body member to and around said sprocket wheel, said resilient member 15 continuing on upwardly in an opposite vacant corner within said body member, said resilient member having openings adapted to receive the projections of the sprocket wheel, and closures for the open ends of the body member.
- 20 3. A lipstick device comprising a hollow body member, a cup adapted to hold lipstick movable within said body member, a resilient member positioned within said body member and attached at its upper end to said cup, a turnable member rotatably attached to the walls of said body member adjacent its lower portion, a wheel operable from the exterior of the device attached to said turnable member, a sprocket wheel attached to 25 said turnable member, said resilient member having a plurality of spaced openings, said resilient member extending down to and around said sprocket wheel so that the projections on the sprocket wheel fit within said openings, said resilient member continuing on upwardly on the opposite side walls within said body member, and removable closures for the open ends of said body member.
- 30

silient member extending down to and around said sprocket wheel so that the projections on the sprocket wheel fit within said openings, said re- 5 silient member continuing on upwardly on the opposite side walls within said body member, re- movable closures for the open ends of said body member, the closure for the lower end of said body member having a bearing adapted to contact the resilient member so that the projections of the sprocket wheel will fit within the openings of 10 the resilient member.

4. A lipstick device comprising a hollow body member, a cup adapted to hold lipstick movable within said body member, a resilient member positioned within said body member and attached at 15 its upper end to said cup, a turnable member rotatably attached to the walls of said body member adjacent its lower portion, a wheel operable from the exterior of the device attached to said turnable member, a sprocket wheel attached to 20 said turnable member, said resilient member having a plurality of spaced openings, said re- 25 silient member extending down to and around said sprocket wheel so that the projections on the sprocket wheel fit within said openings, said re- silient member continuing on upwardly on the opposite side walls within said body member, and removable closures for the open ends of said body member.

JAMES L. YOUNGHUSBAND. 30
